SIGN PANEL

Marilyn Lewis, Beverly Hills, Calif., assignor to Hamburger Hamlets, Inc.

Filed Dec. 15, 1969, Ser. No. 20,494

Term of patent 14 years

Int. Cl. D20—03

U.S. Cl. D96—12

FIG. 1 is a front elevational view of a sign panel showing my new design;

FIG. 2 is an elevational view taken from one end thereof; and

FIG. 3 is a fragmentary perspective view thereof.

I claim:

The ornamental design for a sign panel, as shown.
